COVER FOR RECEPTACLES

Herbert W. Whitaker, East Hartford, Conn.

Application March 9, 1936, Serial No. 67,895

9 Claims. (Cl. 70—165)

My invention relates to that class of devices which are used for closing the filling opening to a receptacle, particularly for fuel tanks, and an object of my invention, among others, is the production of a closure of this type which will prevent access to the interior of the tank except by persons authorized to uncover the opening; and a further object of the invention is to provide a device which will prevent the introduction of liquid except when the opening is uncovered for such purpose; and a still further object of the invention is the provision of a cover which will permit the insertion of a gage or measure to determine the amount of liquid within the tank.

Forms of covers embodying my invention and in the construction and use of which the objects herein set out, as well as others, may be attained are illustrated in the accompanying drawing in which—

Figure 1 is a view in central lengthwise section through a cap embodying my invention.
Figure 2 is a top plan view of the same with the cap removed.
Figure 3 is a view in central lengthwise section through a cap a little different in construction from that shown in Fig. 1.

Figure 4 is a similar view but showing another different construction.
Figure 5 is a top plan view of the structure shown in Fig. 3.

Figure 6 is a view in section through the structure shown in Fig. 4 on a plane denoted by the dotted line 6—6 of Fig. 4.

Figure 7 is an isometric perspective view of the lock case.

In the use of caps for the filling openings of containers prior to my invention it has been a quite common occurrence that the contents of the tank may be surreptitiously removed particularly from tanks containing fuel for explosive engines in boats, automobiles and other vehicles. Another objection to caps for filling openings in use at the present time, particularly in the case of fuel filling stations, is the practice of introducing fuel of a different or inferior quality from that supposed to be contained within the tanks so that the purchaser is not sure of obtaining the fuel which he desires.

It is the purpose of my invention to provide means whereby these objections shall be removed, such a device being illustrated in the drawing herein in which the numeral 6 denotes a fill box such as is used at the filling opening of a storage tank commonly employed in filling stations. This

box has a flange 7 at its outer end and lugs 8 all of which are usually embedded in a flooring 9 of concrete or similar material.

A supporting ring 10 has a flange 11 fitting within a recess at the mouth of the fill box 6, said ring being threaded to fit a threaded hole 12 in the fill box, as shown in Fig. 1 of the drawing. The ring may be secured in place as by means of screws projecting through the flange 11 into the fill box. A lip 13 extends inwardly into the opening at the inner edge of the ring.

A cap 14 is secured to the outer face of the box and the ring 10 as by means of a threaded hub 15 fitting a threaded opening through the ring 10, a gasket 45 being placed between the cap and box if desired.

A locking ring 16 is threaded into the partially threaded hole through the box 6, this ring being an expanding ring, preferably split on one side and having a threaded hole for the reception of a locking screw 17 tapered to fit a tapered threaded opening through the split portion of the ring. The screw being turned tightly into place the ring is locked securely against movement. A lock case 18 has a flange by means of which the case is seated on the lip 13 of the ring 10. This case contains the cylinder 19 of a lock preferably of the pin tumbler type, the barrel 20 of the lock having a latch 21 secured thereto, said latch, as the barrel is turned, locking underneath the ring 16.

The parts of the structure are, when the latch is in engagement with the ring, all secured together, the lock case holding the ring 10 in place against removal and the case itself being held by the latch 21.

In the form of the device shown in Fig. 3 the supporting ring 10 is dispensed with, the lock case 22 being mounted in a shell 23 which may comprise the opening into an ordinary gas tank or the deck plate of a boat. The ring 16 is of similar construction to that hereinbefore described, being screw threaded into the shell and held therein in a similar manner, that is, by an expanding screw which, however, projects across a slot extending into the ring from its side, as shown in Fig. 3 of the drawing. The case 22 is also provided with the cylinder 19 of a pin tumbler lock and with the latch 21 which latches underneath the ring to hold the parts in place.

In the device shown in Fig. 4 a shell 24 is provided having a screw threaded opening to receive a screw threaded support 26 for a lock case 27. The support 26 has a bottom 28 through which a screw 29 projects into the lock case to

hold the latter in place, the screw so engaging the lock case that the latter may be freely turned within the support.

A cylinder 30 containing a barrel preferably of

- 5 the pin tumbler type is located in the case and is connected in any ordinary manner with a locking bolt 31 mounted for reciprocating movement in the bottom of the case, the end of the bolt being engageable with a locking notch 32 formed 10 on the inner wall of the support 26, and preferably in a shoulder 33 upon which the lock case 27 is seated.

In this device when the barrel 37 within the cylinder has been operated to withdraw the bolt 15 31 from the notch 32 the case 27 may be rotated freely within the support 26 and the latter cannot therefore be removed. When it is desired to open the hole 34 through the case this may be done by means of a key inserted in the key barrel 20 in the cylinder 30 which will operate the bolt 31 to engage the notch 32. This locks the case 27 to the support 26 and then by means of the cover 25 the case and the support may be turned to remove them by unscrewing them from the 25 hole 34.

The cover 35 has two ears 36 near opposite edges located in recesses in the lock case 27, the pivots for the cover being located substantially on or close to a diametrical line across the case 30 so that said cover may be effectually used as a thumb piece for unscrewing the support 26.

In the particular structure shown in Fig. 4 the bolt 31 is connected with the barrel 37 by means of a link 38 pivotally eccentrically attached to the 35 barrel and having a pin and slot connection with the bolt as shown in Fig. 6 of the drawing to permit movement of the bolt independently of the link. Springs 39 located in recesses in the bolt exert pressure against the end of the link.

40 With this construction when the barrel 37 is operated to thrust the bolt toward the wall of the support 26 for engagement with the recess 32 therein should the bolt not be located opposite said recess it will strike the inner surface 45 of the support. The barrel 37 may, however, be fully turned to the position shown in Fig. 6, the springs 39 permitting this, and as soon as the bolt is moved opposite the recess 32 it will snap into the recess and lock the parts together.

50 The shells 23-24 may be provided with lugs 49 to engage within recesses of the same shape in the base or the support to which said shells are attached and to which they may be secured as by means of screws through the holes 41, as

55 shown in Figs. 3 and 4 of the drawing. This will prevent removal of the shells from said support as by removal of the screws from the holes 41 for the reason that the shells cannot be turned to unscrew them from the filling pipes 42 as the 60 lugs prevent such turning and the shells cannot be lifted to remove the lugs from their recesses, as said shells are held by the pipes 42.

65 While the structure of Figure 1 is shown to substantially the same scale as the devices of the other figures it will be understood that the device of Fig. 1, owing to its character and manner of use, will be much larger than the devices of the other figures. An important feature of the structure of Fig. 1 resides in a gaging slot 43 of 70 very narrow dimensions extending through the lock case 18 by means of which access may be had to the interior of the tank for a gage 44 for the purpose of determining the amount of liquid within the tank.

75 While a slot has been shown herein as a gag-

ing opening I contemplate that any opening small enough to constitute what I term a "non-filling" opening may be employed irrespective of its shape.

I claim:

1. A cover for the filling opening of a receptacle, said cover comprising a shell, a supporting member separately formed from and removably attached to said shell, a lock case loosely supported by and seated on said supporting member, and a locking member positioned and movable below the bottom of said case for engaging and disengaging action with a cooperating member located on one of said other members to prevent removal of said case and to permit its removal, 15 said case being completely rotatable independently of said supporting member.

2. A cover for the filling opening of a receptacle, said cover comprising a shell, a fastening member separately formed from and removably 20 secured to said shell, a lock case to close an opening through said fastening member, and a lock mounted in said case and comprising a latch positioned and movable below said case and said fastening member and engageable with the latter 25 to secure the lock case in place, said latch being completely revoluble independently of said shell.

3. A cover for the filling opening of a receptacle, said cover comprising a shell, a fastening member screw-threadedly engaged with said shell, 30 means for expanding said member to secure it to said shell, a lock case to close an opening through said fastening member, and a lock comprising a latch engageable with said fastening member to secure the lock case in place. 35

4. A cover for the filling opening of a receptacle, said cover comprising a shell, a supporting member attached to the shell and having a flange seated on a shoulder in a recess in said shell, a fastening member secured to the shell, a lock 40 case carried by said supporting member, and a lock comprising a latch engageable with said fastening member to secure the lock case in place.

5. A cover for the filling opening of a receptacle, said cover comprising a shell, a supporting member screw-threadedly engaged with said shell by means of a flange seated on a shoulder in a recess in said shell and having a supporting lip, a fastening member screw-threadedly engaged 45 with said shell, means for securing said fastening member in place, and a lock case seated on said lip and having a lock including a latch engageable with said fastening member to secure the lock case in place. 50

6. A cover for the filling opening of a receptacle, said cover comprising a shell, a supporting member screw-threadedly engaged with said shell, a fastening member comprising a split ring screw-threadedly engaged with said shell, means for expanding the ring to secure it to said shell, 60 and a lock case seated on said supporting member and including a latch engageable with said fastening member to secure the lock case in place. 65

7. A cover for the filling opening of a receptacle, said cover comprising a shell, a fastening member screw-threadedly engaged with said shell, means for securing said fastening member in place, a supporting member screw-threadedly engaged with said shell and abutting said fastening member, a lock case seated on said supporting member, and a lock including a latch engageable with the underside of said fastening member to secure the lock case in place. 70

8. A cover for the filling opening of a recep-

tacle, said cover comprising a shell, a supporting member screw-threadedly engaged with said shell, a lock case loosely engaged with said supporting member, means for securing said lock case to the supporting member for independent rotation of said lock case, and means for locking said case to said supporting member for simultaneous rotation of the case and member.

5. A cover for the filling opening of a recep-

tacle, said cover comprising a shell, a supporting member attached to said shell, a lock case attachable to said supporting member, locking mechanism borne by said case, and a cover to enclose said mechanism, said cover extending across the case on substantially a diametric line to serve as a finger piece for rotation of the lock case.
